UNITED STATES PATENT OFFICE.

JOHN A. HELLSTROM, OF WHEELING, WEST VIRGINIA.

MANIPULATOR FOR ROLLING MILLS.

Application filed February 27, 1925. Serial No. 12,001.

This invention relates to an improvement in a manipulator for rolling mills, the invention being more specifically an improved drive for the ingot manipulating fingers.

5 This invention has for its chief object the provision of a vertical movement to the manipulator fingers by a revolving shaft.

Another object of the invention is to impart a vertical movement to the lifting fingers through the medium of a revolving shaft which is adapted to travel laterally with the fingers and be driven by a stationary motive power.

10 A further object of the invention is to provide a manipulator including pusher bars carrying a deck which in turn carries a guard and the manipulator fingers, the pusher bars and deck being designed to move laterally across the feed table carrying with 15 it the guard and fingers, the construction being such that it is readily accessible for repair or adjustment and is simple of construction.

Another object of the invention is the provision of the bridge carried by the pusher bars which carries the rocking shaft and universal drive whereby they are located to be protected from the heat of the ingot or slab or other metal being worked upon.

30 A still further object of the invention is to provide a more uniform and positive motion to the ingot manipulating fingers through a more simplified construction than heretofore known.

35 Another and further object of the invention is the provision of a manipulator for use with the feed table of a rolling mill which is simple of construction and using a comparatively small number of parts and which in 40 operation is easily and simply controlled to impart the desired extent and direction of movements.

45 A further object of the invention is to provide a novel construction whereby a rocking motion is imparted to a shaft through the medium of a revolving shaft.

50 Other further objects, novel features of construction and improved results of the invention will appear in the specification and in the appended claims.

In the accompanying drawings wherein there is shown the preferred embodiment of my invention, Figure 1 is a top plan view of a portion of a rolling mill showing the table 55 at one side of the reducing rolls and the im-

proved manipulator drive and its associated parts applied thereto.

Figure 2 is a transverse sectional view of that side of the manipulator carrying the fingers.

60 Figure 3 is an enlarged detailed transverse sectional view of the universal drive.

Figure 4 is an enlarged detailed plan view, partly in section, showing the drive connection to the universal drive shaft.

65 Figure 5 is a plan view showing a modification of use of the universal drive.

Broadly a manipulator is not new. Ordinarily the rocking shaft of a manipulator is located on top of the guard and is driven with miter or beveled gears from a square shaft or the like. However the square shaft does not revolve but is rocked by means of links and levers connected to a crank shaft which is driven by motor through spur gears or the like.

70 The common construction just described has certain disadvantages. With the rocking shaft located immediately on the guard, the rocking shaft is subjected to the heat 80 from the work with the result that the rocking shaft will soon become out of line with its bearings. Heretofore this has been overcome by putting flexible joints or couplings 85 on the rocker shaft between each of its bearings. It is very difficult to keep the driving miter or beveled gear bearings in proper relation due to the warping of the guide and therefore the result is that the gears must 90 be cut with more clearance between their teeth than is considered good practice. The flexible joint in the rocking shaft therefore is an undesirable feature as the joints must be constructed with clearance and the continuous hammering and jolting to which they 95 are subjected will add even more clearance with the result that the manipulator fingers will not each lift the same nor can they be kept in a straight line.

100 Furthermore the constructions heretofore used have the disadvantage of rocking the square shaft by means of levers, connecting rods, crank shaft and gears or the like to a motor. The upkeep and loss motion in this construction due to wear makes for a high 105 upkeep with a poorer operation. Due to the fact that the square shaft rocks rather than rotates there results a considerable amount of wear in the square hold in the rocking lever in which the square shaft slides. This 110

in turn results in the loss of part of the stroke to the manipulator fingers proper. It has also been found that the manipulator fingers will sometimes fail to stop below the 5 table rollers on the down stroke as the momentum of the moving parts from the motor to the fingers, even if a limiting switch is in use, will not stop the crank shaft in each horizontal position and the wear of the 10 square hole in the rocking lever will cause the shoulders of the fingers to project above the table rollers. This results often times in the ingot or work sticking against the fingers when being passed through the shaping rolls. 15 With the exception of the improvements which will be hereinafter pointed out the rolling mill including the feed table and manipulator is of a usual and common construction which comprises the reducing rolls 6 on 20 either side of which is a feed table composed of a plurality of rollers 7 journaled or otherwise suitably supported in the side bars or frame 8 of the table and driven through the medium of the bevelled gears 9 in the 25 usual or customary manner. Only one of the feed tables is shown in the drawings, it being understood of course that a table similar to the one shown is provided at the opposite side of the reduction rolls. 30 The present embodiment of mill shown consists of a pushing and tilting unit located at one side of the reduction rolls. The pushing unit is located at the left side and the tilting unit at the right side of the feed. 35 table. It may be advantageous to reverse the positions of these units depending upon the condition of the mill lay out in which they are to be utilized. This reversal of parts can of course be easily and simply accomplished. As heretofore mentioned there may 40 be a manipulator at both sides of the shaping rolls so that the ingot, slab or other work can be pushed or turned on either entering or delivery side of the working rolls. Additionally to meet the special requirements 45 the manipulator at one side of the shaping rolls may be a pushing and tilting unit while the manipulator at the opposite side may comprise two pushing units. It will of course 50 be understood that where manipulators are used at both sides of the shaping rolls or rolling mill the power shaft for the pusher bars is so connected that the guards on both of the manipulators move parallel and in 55 unison.

The mill shown in the drawings is two high, that is the bottom shaping roll is stationary while the top roll is moved up and down whereby an ingot is reduced to a 60 bloom, billet, slab, beam, etc., or other shape as may be desired. In producing slabs the guards are pushed together to hold the slab and form a continuous guide on both sides of the shaping rolls which prevents the slabs 65 from twisting during the operation of edg-

ing them. The turning or manipulating fingers are operated a number of times during the reduction of an ingot to a particular shape, this tilting or turning taking place at a position on the feed table dependent on 70 the location in the shaping rolls of the particular pass it is desired that the ingot enter.

When turning an ingot the pushing unit and guard is moved towards the ingot and during the turning thereof by the manipulator fingers the tilting unit is pushed forward so that when the ingot is partly tilted it will be held between the guards of the pushing and tilting units. The pushing unit is then withdrawn from the ingot and the 80 tilting unit pushed forward so as to turn the ingot on the table. By this method the ingot is prevented from sliding off the shoulders of the tilting or manipulating fingers.

To accomplish the manipulation of the 85 ingot which is described the manipulator comprises the tilting unit A shown at the right side of the feed table B and the pushing unit C shown at the left side of the table. The tilting unit is provided with a guard 10 mounted in front of the deck 11 which is supported upon the pusher bars 12 while the pushing unit comprises the guard 13 mounted at the front ends of the pusher bars 14. The pusher bars and their guards are arranged to move laterally over the feed table 95 rolls. The movement of the tilting unit pusher bars is effected through the gear 15 having engagement with the rack 16 of the bars. The gear 15 is driven by a suitable 100 motor 17, gears 18 and shaft 19. The pusher bars are provided with rollers 20 and 21 which run on V-shaped tracks 22. Attention is directed to the fact that the roller 20 is below the track while the roller 21 is 105 above the track and journaled in a suitable housing 23 on the top of the pusher bar.

The movement of the pusher bars and guard of the pushing unit is accomplished in practically the same manner, in this instance 110 the driving power being a motor 24, gears 25, shaft 26, the pusher bars being provided with racks and wheels adapted to engage a V-shaped track in a similar fashion as the construction which is above described in respect to the tilting unit.

Suitably located, as between the pusher bars of the tilting unit there is provided a suitable motor 27 which is fastened upon a stationary base 28. This motor is the driving power for the manipulator fingers. The power is transmitted to the fingers through the motor shaft 29 carrying a gear 30 which meshes with the gear 31. These gears are within a suitable housing 32 mounted upon a stationary base 33.

A gear 31 is keyed to the hub 34 which hub is provided centrally with a square hole adapted to slidably receive the square shaft 35. The housing 32 for the gears is made in 13

two parts and to form bearings 36 for the hub. Preferably the hub is provided at its ends with bronze bearings 37 engaging the housing bearings 36.

5 The motor base 28 and gearing base 33 are in a horizontal alignment with the universal drive D mounted on the bridge or deck 11 so it is possible to connect one end of the shaft 35 to the universal drive. To 10 take care of any wear or in the event that the parts do not remain in alignment there is provided a flexible coupling 38 between the motor 27 and the gear 30 and a flexible coupling 39 between the shaft 35 and the 15 universal drive.

By reference to the drawings, particularly Figures 2 and 3 it will be seen that the universal drive is enclosed in a two part housing 40 mounted upon the bridge or deck 11.

20 The end of the housing adjacent the universal coupling 39 is reduced or constructed to receive a bearing 41 in which is rotatably supported the stub shaft 42 of the wheel 43 of the universal drive. The connection 25 between the shaft 35 and the stub shaft 42 is made at the flexible coupling 39.

Mounted upon the bridge 11 in suitable bearings 44 there is a rocker shaft 45 which passes through the universal drive housing 40 which is positioned intermediate its length. That portion of the shaft 45 within the housing of the universal drive carries a hub 46 keyed to the shaft as at 47 and provided with outwardly extending 35 trunnions 48. A pitman 49 provided with a ball-shaped end 30 which engages the rotatable bearing 51 carried by the inner face of the wheel 43. The outer perimeter of the wheel 43 is supported on suitable roller bearings 52 positioned between the wheel 43 and the housing 40. The other end of the pitman 49 is forked-shape being provided with a yoke portion 53 to permit the placing of the yoke over the hub trunnion 48. The yoke 53 is held in locked position by suitable pins 54. As clearly appears the pitman is pivotally supported by the trunnions 48, suitable bronze bushings 55 being interposed between the trunnions and the pitman yoke.

50 As the drive is entirely enclosed in the housing 40 it can run in oil or grease to eliminate wear of the revolving parts. The housing is provided with a removable cover 56 to permit access to the parts.

55 It will be seen that when the wheel 43 is revolved in its connection through the shaft 35 that the ball end 50 of the pitman will be rotated and that the forked end of the pitman 49 will turn on the hub trunnions 48. The foregoing will impart a rocking motion to the shaft 45 and the distance through which the shaft 45 is moved will depend on the distance of the ball end 50 of the pitman from the center line of the wheel 43. During the rotation of the wheel

43 the center line of the pitman 49 will describe a cone shape with the base of the cone equal in diameter to the diameter of the circle described by the rounded end 50 of the pitman.

70 The manipulator fingers or bars are indicated at 57 and are positioned in front of the guard 10 being pivotally attached at 58 to the outer end of the rocker shaft arms 59 which through their attachment to the rocker shaft 45 support the fingers in position. The lower end of the fingers 60 extend to a point below the table rolls 7 and are provided with shoulders 61 which are normally beneath the top line of the table rolls so that 80 when the fingers are lifted these shoulders will engage beneath the ingot or work 62 and turn the same upon the table. The manner of operation of the fingers upon the work is illustrated in Figure 2 of the drawings. 85

It will now be quite evident that the pusher bars move the guards across the table. In respect to the tilting unit the pusher bars also move the bridge or deck laterally across the table carrying therewith the manipulator fingers, rocking shaft and rocking shaft arms and the universal drive. Through reason of the flexible coupling 39 and square shaft 35 being connected to the universal drive the shaft 35 will move laterally with 90 the bridge the square shaft sliding through the square opening in the hub 32 of the driving gear 31.

95 It will be further seen that one revolution of the square shaft 35, through the universal drive, rock shaft and rock shaft arms will lift the manipulator fingers up and down. Through reason of the sliding connection of the square shaft 35 it is possible, from a stationary motor gear, to operate the manipulator fingers at any position of the guard or bridge on the table. 100

105 The improved construction of the invention here adds many advantages. The bridge or deck on which the rocking shaft and universal drive are located is protected from the heat of the ingot or work and therefore will not warp. There is no need for the flexible joints or couplings between the bearings of the rocking shaft, no gears, levers, links or the like as in the common construction and therefore there is considerable less weight to the device. By reducing the weight there is less momentum of the moving parts which 110 lift the fingers. The complete revolving of the square shaft during the operation of the fingers will produce a more uniform motion of the fingers and there will be no loss of distance in the stroke or lift of the fingers due to any wear in the square hole through which the square shaft slides. It is also believed that the particular construction of V-shaped track for the pusher bars together with the V-shaped wheels, one of which is mounted 115 below the pusher bars and the other in the 120

housing upon the top of the pusher bars, is new and operates to better advantage. Heretofore it is believed to have been the practice for the pusher bar to be provided with a 5 bronze slide in place of the wheel 21 and although a wheel is used and positioned such as the wheel 20 the same is rotated on a flat surface and to eliminate side motion to the pushing bars bronze linings have been used on the 10 sides of the pushing bars. Furthermore there is present in this invention at the front end of the pusher bars spring bumpers 63 to prevent the manipulator guard and fingers from striking the table girder on the return 15 stroke of the guard.

Attention is directed to the fact that the universal drive principle of this invention can be used to solve a number of mechanical problems. For instance, as appears in Figure 20 3 of the drawings, the stub shaft 42 can carry a gear or coupling 64 which may be driven by a motor or any other suitable motive power.

In Figure 5 appears a modified form of 25 the invention showing another manner in which the universal drive principle, wherein a sliding motion is imparted to one shaft by another rotating shaft, is utilized.

In the modified form of the invention the 30 universal drive D the construction of which has heretofore been described has connection with a stub shaft 65 taking the place of the rocker shaft 45 of the manipulator. The stub shaft 42 of the drive is extended 35 to an outboard bearing 66 and driven through the medium of a suitable motor 67 and gears 68 and 69. The connection can be made to one or both ends of the shaft 65 as clearly appears through the medium of 40 couplings 70 and shafts 71. A rocking motion is of course imparted to the shafts 71 and this in turn by a suitable connection, for example as shown, through a toothed quadrant 72, engaging a rack 73 or the like 45 adapted to slide in a guideway 74, there can be produced a fixed sliding travel. By the use of a two arm connection with the shafts 71 there could be produced both a sliding or rocking motion by the rocking shaft 71.

Attention is directed to the fact that by 50 the use of this invention on a manipulator the driving of the manipulator fingers is accomplished by a much simplified construction and that the driving parts of the fingers is entirely above the roller table.

Having thus described my invention what I claim and desire to secure by Letters Patent is:—

1. In combination with the feed table of 60 a rolling mill, a manipulator including a side guard adapted to be moved laterally over the feed table, a plurality of turning bars for turning the work on the table, said bars being mounted for endwise movement 65 in vertical planes, a rocking shaft and a

driven revolving shaft, a universal connection between said shafts, and said turning bars having connection with said rocking shaft, whereby endwise movement is im- 70 parted to the bars.

2. In combination with the feed table of a 75 rolling mill, a rocking-shaft a guard movable laterally over the feed table, a plurality of turning bars supported by the rocking shaft and adapted to turn the work on the table, a driven revolving shaft for imparting endwise movement in vertical planes to the turning bars, and a universal connection interposed between said revolving shaft and said rocking shaft.

3. In combination with the feed table of a 85 rolling mill, a plurality of turning bars adapted to turn the work on the table, a rocking shaft for imparting endwise movement in vertical planes to the turning bars, the turning bars and rocking shaft adapted to be moved over the table, a revolving shaft driven by stationary power means for imparting rocking motion to said rocking shaft, a universal connection, and said universal connection interposed between the revolving shaft and the rocking shaft. 90

4. In combination with the feed table of a 95 rolling mill, a manipulator including a side guard and deck, adapted to be moved laterally over the feed table, a rocking shaft mounted on said deck, turning fingers operatively connected with said rocking shaft and movable therewith for turning the work on the table, a rotating shaft driven by stationary motive means, a universal connection, and said rotating shaft and rocking shaft operatively connected through said universal connection, whereby a rocking 100 movement is imparted to the rocking shaft by said revolving shaft.

5. In combination with the feed table of a 105 rolling mill, a rocking-shaft, a plurality of turning fingers operatively connected with the rocking shaft and adapted for lateral movement across said table for turning the work thereon, a revolving shaft for imparting a rocking movement to said rocking shaft, a universal connection, said universal connection interposed between said revolving and said rocking shafts, and said rotating shaft having sliding positive engagement with a stationary motive power, whereby said revolving shaft is movable with the 110 rocking shaft and turning bars. 115

6. In combination with the feed table of a 120 rolling mill, a guard and deck movable laterally over the table, guides supporting the guard and deck and extending laterally outwardly over the table, turning bars for 125 turning the work on the table movable laterally with the guard, means for elevating the turning bars comprising a rocking shaft mounted on the deck at the rear of the guard and parallel therewith, the turning 130

bars operatively connected to the said rocking shaft, a universal connection, a driven revolving shaft, and said rocking shaft and revolving shaft operatively connected through the medium of said universal connection, whereby the revolving shaft imparts a rocking motion to the rocking shaft.

7. In combination with the feed table of a rolling mill, a guard movable laterally over the table, a deck positioned behind said guard, said guard and deck supported by guides extending laterally outward from the feed table, a rocking shaft mounted on said deck, turning bars for turning the work on the feed table and operatively connected with and supported by said rocking shaft, a revolving shaft having movable progressive engagement with stationary motive power, a universal connection interposed between said revolving and said rock-shaft, and said universal connection causing the revolving shaft to impart a rocking motion to the rocking shaft, whereby the turning bars are connected endwise in a vertical plane.

8. In combination with the feed-table of a rolling mill, a rocking-shaft, turning bars for turning the work on the table having operative engagement with and supported by the rock-shaft, said rock-shaft and turning bars adapted to be moved laterally over the table, a revolving member in fixed position having a square opening therein, a shaft having a square portion adapted for sliding engagement with the square opening of the revolving member and adapted to be rotated thereby, and operative engagement between the square shaft and the rocking shaft for imparting a rocking motion to the rock-shaft.

9. In combination with the feed-table of a rolling mill, a manipulator including a side guard and deck supported by and adapted to be moved laterally over the feed-table by guides extending laterally outward from the deck, the guide provided with grooved wheels for engaging a track, means to actuate the guides, a plurality of turning bars operatively connected with and supported by a rock-shaft mounted on said deck, a revolving shaft for imparting a rocking movement to said rock shaft, and said rotating shaft having sliding positive engagement with a fixed motive power, whereby said revolving shaft is movable and progresses with the rock-shaft and deck.

10. In combination with the feed-table of a rolling mill, a guard movable laterally over the feed-table and carrying a rock shaft, turning bars operatively connected with and supported by said rock-shaft and adapted to turn the work on the table, a revolving shaft, means for driving said revolving shaft, and a universal connection between the revolving shaft and rock-shaft, whereby said revolving shaft imparts a rocking motion to the rock-shaft for imparting endwise movement to the turning bars.

11. In combination with the feed table of a rolling mill, a guard movable laterally over the feed table, a bridge back of said guard and movable therewith, a rock shaft mounted on the said bridge, manipulating fingers adapted to turn the work on the table, said manipulating fingers supported by and actuated entirely by said rock shaft, a revolving shaft, means for driving said revolving shaft, and a universal connection between said revolving and rock shaft, whereby said revolving shaft imparts a rocking motion to the rock shaft for imparting endwise movement to the turning bars.

12. The combination with the feed table of a rolling mill, a guard movable laterally over the feed table, a rock shaft, manipulating fingers operatively connected with and supported by said rock shaft and adapted to turn the work on the table, revolving and driving means for said rock shaft, a universal connection between said rock shaft and said revolving shaft, and said rock shaft and universal connection being mounted upon a bridge back of said guard, whereby said parts are removed from the heat zone of the feed table.

13. In combination with the feed table of a rolling mill, a rock shaft mounted to be moved laterally over said table, a revolving power shaft, universal connection between said shafts whereby a rocking motion is imparted to the rock shaft, and manipulating fingers supported and actuated solely by said rock shaft for turning the work on the table.

14. A construction such as defined in claim 13, the manipulator fingers having a single crank connection with the rock shaft and supported in an extended position in front thereof.

In testimony whereof I hereunto affix my signature.

JOHN A. HELLSTROM.
